Inventor
A. L. Cushman

UNITED STATES PATENT OFFICE.

ABE L. CUSHMAN, OF CONCORD, NEW HAMPSHIRE, ASSIGNOR TO JOHN A. WHITE, OF SAME PLACE.

DUST-GUARD FOR CAR-AXLE BOXES.

SPECIFICATION forming part of Letters Patent No. 357,656, dated February 15, 1887.

Application filed December 16, 1886. Serial No. 221,782. (No model.)

To all whom it may concern:

Be it known that I, ABE L. CUSHMAN, a citizen of the United States, residing at Concord, in the county of Merrimac and State of New Hampshire, have invented a new and useful Improvement in Dust-Guards for Car-Axle Boxes, of which the following is a specification.

My invention relates to improvement in dust-guards for car-axle boxes in which blocks operated by springs in a casing act in conjunction with a car axle or journal.

The object of my improvement is, first, to provide a dust-guard that may be used on any car-box; second, to provide a dust-guard positive against the entrance of dust into the box or the exit of oil from the box; third, a dust-guard that is simple in construction, easily operated, and repaired at small cost. I attain these objects by the mechanism illustrated in the accompanying drawings, in which—

Figure 1 is a side view with a portion of the side removed to show the guard spring and receptacle; Fig. 2, a sectional view on line $a a$ through the guard and box, showing the guard in position; Fig. 3, a section of the guard removed.

Similar letters refer to similar parts throughout the views.

The axle box or housing A may be any kind of a car-box, if the inner end is provided with a chamber or receptacle, C, for holding the guard B, and slot f at the top of the box opening into the dust-guard chamber for the reception of the dust-guard B.

The frame or casing B is preferably made of iron on account of having the guards $d d$, which are made of any kind of wood suitable for that purpose, as thick as possible.

The guards d are made in four sections. The ends that come in contact with the axle are made to conform with the outside periphery of the journal or axle D, the outer ends being

made nearly rectangular, except one corner, which is made to fit the casing or frame B, the outer ends also being provided with a pin, e, which guides the spring c and holds the block in contact with the axle to take up the wear and prevent the dust from passing through between the guard and axle. The casing is so constructed that the circular ends of the guards $d d d d$, when the points come in contact with each other, will form a circle of the same diameter as the outside periphery of the axle. (See Fig. 2.)

To admit of the necessary vertical play of the casing B and dust-guard sections $d d d d$, the casing is made shorter than the dust-guard chamber or receptacle C, and the opening of the receptacle f closed, in the usual way, by driving in a wedge adapted to the said opening. The sections d of the dust-guard, when in their normal position, may be moved apart in a central direction for the purpose of receiving the axle D.

The springs $c c c c$ may be made of any material suitable for that purpose, and may be in any position if made to act on the sections $d d d d$ and bring them in contact with the axle D.

I am aware that prior to my invention dust-guards for car-axle boxes have been made. Therefore I do not claim the combination, broadly; but

What I do claim as my invention is—
In a dust-guard, the combination of a casing, B, having four receptacles for holding the dust-guards $d d d d$, and the guards operated by springs $c c c c$ toward the center of the axle D, to take up the wear of the guards, as set forth and described.

ABE L. CUSHMAN.
